UNITED STATES PATENT OFFICE.

PAUL R. ZINSER, OF CINCINNATI, OHIO, ASSIGNOR TO THE CINCINNATI COFFIN COMPANY, OF CINCINNATI, OHIO, A CORPORATION OF OHIO.

DESIGN FOR A LUG FOR CASKETS OR COFFINS.

40,947.

Specification for Design.

Patented Oct. 18, 1910.

Application filed August 22, 1910. Serial No. 578,488. Term of patent 7 years.

To all whom it may concern:

Be it known that I, PAUL R. ZINSER, a subject of the Emperor of Germany, and a resident of Cincinnati, county of Hamilton, and State of Ohio, have invented a new, original, and ornamental Design for Lugs for Caskets or Coffins, of which the following is a specification, reference being had to the accompanying drawing, forming a part thereof.

The figure is a plan view of a lug for caskets or coffins, showing my new design.

I claim—

The ornamental design for a lug for caskets or coffins, as shown.

PAUL R. ZINSER.
